UNITED STATES PATENT OFFICE.

HORACE JOHNSON, OF AKRON, NEW YORK, ASSIGNOR OF ONE-HALF TO
TIMOTHY W. JACKSON, OF SAME PLACE.

WAGON-STAKE HOLDER.

SPECIFICATION forming part of Letters Patent No. 317,138, dated May 5, 1885.

Application filed August 28, 1884. (No model.)

To all whom it may concern:

Be it known that I, HORACE JOHNSON, a citizen of the United States, residing at Akron, in the county of Erie and State of New York, have invented certain new and useful Improvements in Wagon-Stake Holders, of which the following is a specification, reference being had therein to the accompanying drawings.

My invention relates to the construction of a metal stake-holder and stake, and will be understood as hereinafter set forth and claimed.

In the drawings, Figure 1 is a perspective of the holder, and Fig. 2 is a side elevation of the holder and stake set upon a bolster.

A is the holder, cast of a single piece of metal. It has the socket *a* for the stake *C*. The holder *A* is formed with side jaws, *c c*, to pass down the sides of the bolster *B*, as shown, and an end plate, *c'*, to cover the end of the bolster outside of the stake. Openings *g* for bolts may be formed in the body of the holder in the jaws *c c* and in the extension *c'*, to permit the fastening of the stake to the holder and of the holder to the bolster.

On the interior and exterior faces of the holder *A* are provided flat rectangular depressions *f*, in which rest the ends of the plates *f'*, which are secured upon the stake *C*.

These plates *f'*, resting in the depressions *f*, give stiffness and security to the stake, preventing lateral wear and play of the stake. The plates *f'*, with their lower ends resting in the bottom of the depressions *f*, hold the stake stiffly against pressure from the inside or load. When the load comes against said plates and the holder, the stake will be held very securely, and will not wear upon nor tend to break the top of the holder, as might otherwise be done.

I am aware that sockets formed of a single piece have been known, and that they have had side jaws and end extensions, and I do not claim such; but

What I do claim is—

The combination of the wagon-stake holder *A*, having the jaws *c c* and extension *c'* and socket *a*, and provided with the flat rectangular depressions *f*, with the stake *C*, having the plates *f'* on the sides thereof, adapted to rest in the depressions *f* and hold the stake, substantially as and for the purpose set forth.

In testimony whereof I affix my signature in presence of two witnesses.

HORACE JOHNSON.
